UNITED STATES PATENT OFFICE.

JAMES W. IVORY, OF PHILADELPHIA, PENNSYLVANIA.

TOOTH-FILLING IMPRESSION DEVICE.

1,182,376.

Specification of Letters Patent.

Patented May 9, 1916.

Application filed October 7, 1915. Serial No. 54,488.

To all whom it may concern:

Be it known that I, JAMES W. IVORY, a subject of the King of Great Britain, residing in the city and county of Philadelphia, State of Pennsylvania, have invented a new and useful Tooth-Filling Impression Device, of which the following is a specification.

My invention consists of a tooth-filling impression device embodying a matrix which is adapted to cause a conformation to the contour of the tooth of certain materials by which a cavity in said tooth is to be filled, either by an inlay where wax is used as a model for the subsequent casting, or where the filling is of a plastic nature, the device being intended to model into the cavity of the tooth any plastic material or wax models of any inlay material, giving the same a natural contour to the outlines of any wall of the tooth in which such inlay or filling is to be inserted.

The matrix is provided with a holder or carrier for the convenient manipulation of the same.

The invention is satisfactorily illustrated in the accompanying drawing, but the important instrumentalities thereof may be varied, as long as they are included in the scope of the claims.

Figure 1 represents a perspective view of a tooth-filling matrix device embodying my invention. Fig. 2 represents a perspective view of the matrix member thereof. Fig. 3 represents a vertical section of a portion on the line $x-x$ Fig. 4. Fig. 4 represents a horizontal section of a portion on the line $y-y$ Fig. 1. Fig. 5 represents a perspective view of the matrix member in normal condition. Figs. 6, 7 and 9 represent different forms of carriers that may be employed for the matrix member. Fig. 8 represents the matrix held in operative position.

Similar numerals of reference indicate corresponding parts in the figures.

Referring to the drawings, 1 designates a matrix which is formed of a band piece or body of sheet metal or other suitable material and composed of the front wall 2, the side walls 3, the top wall or tip 4, and the outturned tongues 5 on the terminals of the side walls 3.

6 designates a carrier for the matrix, the same being composed of the side arms 7 forming a bifurcation and the handle 8 which are connected with said arms 7, the

latter having therein the slots 9 which are adapted to receive the tongues 5 of the matrix. On said arms are the slides or catches 10 which are connected with the same by means of the screws 11 which pass through longitudinally-extending slots 12 in said catches and are secured to said arms. On the forward ends of said catches are the inwardly-extending lips 13, it being noticed that when the tongues of the matrix are fitted in the slots 9 they are bent forward therefrom, as most plainly shown in Figs. 1 and 4, when the catches are moved toward said tongues, and the lips 13 introduced into the slots 9 back of the tongues 5, thus locking or wedging tightly said lips with said tongues, and consequently connecting the carrier and matrix firmly together and adapting the latter to be manipulated by the former. It is evident as the catches are somewhat resilient they may be drawn out laterally from the arms 7, whereby the lips 13 emerge from the slots 9 when the tongues 5 are no longer controlled by said lips, and thus the matrix may be readily disconnected from the carrier 6 and vice versa. The catches are provided with knobs 14 for evident purposes.

In Figs. 6 and 7 I show forms of carriers different from each other, and the one shown in the previous figures. In Fig. 6 I show the terminals of the arms 7 continued into the bow 15 in the crown of which is fitted the screw 16, the inner end of which is pivotally connected with the toggle levers 17 by which provision the arms 7 may be separated or brought toward each other, and the width of the matrix accordingly adjusted. On the outer end of the rod 16, the same being threaded, is fitted the nut 18 which is adapted to bear against the crown of the bow 15, its object being to move the rod 16 in opposite directions, and thus open or close the toggle levers 17, as the case may be. In Fig. 7 the same result is produced by connecting with the arms 7 the levers 19 which are pivoted to the strap 20, to the center of which latter is secured the screw 21 on which is fitted the nut 22, the same having a conical surface 23 which is adapted to ride upon the inner side of the levers 19, so that in one direction of rotation of the nut 22, said levers will be separated, and the arms 7 accordingly closed, and with them the matrix will reduce its diameter. The opening motion of the arms

7 and consequently of the matrix will be effected by means of the spring 24 which is interposed between the inner ends of the levers 19 and connected therewith. As the 5 cavities of the teeth are multiform different styles of tooth filling matrix forms will be constructed, and all will be adapted to be engaged to the carrier.

The operation is as follows:—The cavity 10 is properly prepared for the filling or inlay. The matrix is now fitted to the carrier, and being held by it is placed around the tooth forming the lost wall and cusp of the cavity that is to receive the filling or inlay. The 15 wax or filling material is placed in the cavity of the tooth and compressed by a suitable instrument against the walls of said cavity and the matrix. The tip 4 of the matrix is now pressed down over the 20 surface of the tooth and burnished to the proper form.

The matrix material for plastic fillings or wax inlays is usually made from thin metal, or celluloid, and it can be held 25 readily or controlled by the operator in molding the filling or by the use of the carrier, Fig. 1.

In the various operations a longer time may be necessary for the filling to set. In 30 which operations the constructions shown in Figs. 6 and 7, while also acting as carriers have the advantage of engaging the matrix with the tooth so as to tighten the matrix to conform to the outer walls of the cavity 35 in the tooth beyond the margin and against the buccal and lingual faces thereof, and be held firmly by such engagement with the tooth so as to draw the matrix tightly against the tooth conforming the filling or 40 wax inlay to the contour of the walls of the tooth, the matrix forming the missing wall of the cavity, which matrix when removed leaves a water tight margin of the filling or 45 wax inlay, with the walls of the cavity and a smooth outer surface. Heretofore, matrix bands have been made with apertures in which the retainer engages, in this tooth-filling impression device the metal or celluloid projection of the matrix engages with 50 the carrier and is held rigidly and firmly by the latter by its interlocking with the arms of the same.

Copies of this patent may be obtained for five cents each, by addressing the "Commissioner of Patents, Washington, D. C."

As shown in Fig. 8, the matrix may be reversed so that the front arms and sides of the matrix are curved within the arms of 55 the carrier as will be necessary when the inlays and plastic fillings are to be inserted in an anterior proximal cavity. The matrix may be made with or without the extension 4 that forms the cusp or lost grinding face 60 of the tooth according to the nature of the operation.

In Fig. 9 I show one of the side arms as adapted to slide on the adjacent portion of the carrier, it having at its rear end a boss 65 or flange which freely embraces said portion, and at the front end a lip which is adapted to enter the slot of the carrier and engage the adjacent portion of the matrix, 70 as in the previous instances.

Having thus described my invention what I claim as new and desire to secure by Letters Patent, is:—

1. A carrier for a matrix band composed of an arm, a movable catch on said arm, 75 said arm having an opening therein to receive a terminal member of said band, said catch having a forward terminal member adapted to enter said opening and wedge tightly said terminal member of said matrix 80 band.

2. A matrix band having on a terminal thereof a laterally projecting tongue, an arm adapted to carry said band and having an opening in the forward end thereof to 85 receive said terminal tongue of the matrix band, and a movable catch mounted on said arm having on its forward end a lip which is adapted to enter said opening and hold tightly the terminal tongue of the matrix 90 band on said arm.

3. A matrix band having on its side a laterally-extending tongue, a carrier for said band having on its forward end an opening adapted to receive said tongue, a 95 resilient catch on said arm having a longitudinally adjustable connection therewith, the forward portion of said catch being adapted to engage said tongue of the band and wedge the same tightly on said carrier. 100

JAMES W. IVORY.
